HYDROPLANE BOAT HULL FORM

Charles Douglas Van Patten, Flint, Mich.

Application August 20, 1945, Serial No. 611,537

9 Claims. (Cl. 114—66.5)

1

This invention relates to power boats, vessels, seaplanes and flying boats of the type having a hull or hulls adapted to provide hydrostatic floatation while at rest in the water and a planing or hydrodynamic lifting reaction when forwardly propelled through the water, the principal object being the provision of a new and novel form of hydrodynamic lifting surfaces for such craft which include those forms commonly known as hard-chine hulls and hydroplanes.

Objects of the invention include the provision of a novel form of planing or lifting surfaces for a boat of the type described by the use of which the area of wetted surface is considerably reduced, as compared with conventional constructions, during movement of the boat through the water and by the use of which the entrance wave is prevented from coming in contact with the greater portion of those surfaces which it is not actually reacting against to produce lift; the provision of a planing surface construction for boats and the like so constructed and arranged as to utilize whatever hydrodynamic lifting effort is required and no more; the provision of a planing surface or surfaces for a boat or the like which will so condition the water over and through which the boat passes as to reduce the surface frictional resistance of the boat to forward motion; the provision of a planing surface construction by the use of which the wave making or residual resistance is substantially reduced, as compared to conventional forms, during movement of the boat through the water; and the provision of a planing surface or surfaces for a boat in which the tendency to compress the water against the planing surfaces or any part contiguous thereto during its movement outwardly from the keel is largely eliminated.

Other objects consist in the provision of a planing surface or surfaces for boats or the like, the use of which largely eliminates the adhesion of water contained in the entrance wave to the bottom of the boat and the consequent abnormal raising of that entrance wave, thereby permitting the use of more easily driven and more seaworthy shapes than are possible in conventional constructions; the provision of a planing surface or surfaces so constructed as to considerably reduce the air resistance of the boat to forward movement by permitting a part of the air that would normally be forced aside to pass under the boat; the provision of a novel form of planing surfaces for a hydroplane of the stepped type so constructed as to greatly reduce the disadvantages present in conventional constructions due to the

2

formation of a region of low atmospheric pressure immediately abaft or back of such step or steps; and the provision of a planing surface or surfaces for boats or the like, the use of which largely overcomes the depressant or weighing-down effect of the atmospheric head on the boat, wherein such head tends to fill the trough immediately rearward of the entrance wave, by allowing atmospheric access and air passage immediately beneath such surfaces.

Further objects include the provision of a planing surface or surfaces for a boat of the class described having special provision for reducing the area in contact with the water in accordance with the weight and speed of the boat without impairing the lateral stability of the boat either in turning or moving in a straight line; the provision of a boat planing surface or surfaces so constructed as to materially increase the directional stability over that obtained with conventional constructions; and the provision of a planing surface or surfaces for a boat of the class described by the use of which the longitudinal stability is increased, as compared with conventional constructions, without increasing the area of wetted surface over that required for most efficient planing of the boat.

Still further objects include the provision of a boat of the class described in which a series of generally longitudinally extending jogs on opposite sides of the keel extend in either parallel relationship to each other and to the keel or in converging relationship with respect to the keel and/or to each other, toward the stern of the boat, and in which each of the generally longitudinally extending jogs is made up of a plurality of shorter portions, preferably parallel with each other as viewed in plan, and each displaced or offset toward the keel from that one immediately forwardly thereof; the provision of a boat of the class described having a planing surface or surfaces of the above described type in which each such portion of a jog is offset from the next preceding or following portion by a distance no greater than the width of the intersected jogged surface; and the provision of a boat of the class described, in which the jogged and offset surfaces may be conveniently provided by suitably lapping the hull strakes; the provision of a boat of the class described having a planing surface or surfaces of the above described type so formed as to have the generally longitudinally extending jogs tapering in depth to zero at their forward and/or rearward ends.

Still another object of the invention is the pro-

vision of a planing surface structure for a flying boat or seaplane which will enable it to more readily and easily lift from the water than is possible with conventional structures.

The above being among the objects of the present invention, the same consists in certain novel features of the construction and combinations of parts to be hereinafter described with reference to the accompanying drawings, and then claimed, having the foregoing and other objects in view.

In the accompanying drawings which illustrate suitable embodiments of the present invention and in which like numerals refer to like parts throughout the several different views:

Fig. 1 is a side elevational view of a planing type of boat, commonly known as a hydroplane, in which a suitable embodiment of the present invention is incorporated;

Fig. 2 is a bottom view of the boat shown in Fig. 1;

Fig. 3 is an enlarged transverse sectional view of the boat shown in Figs. 1 and 2 taken on the line 3—3 of Fig. 2;

Fig. 4 is an enlarged transverse sectional view of the boat shown in the previous figures taken on the line 4—4 of Fig. 2;

Fig. 5 is an enlarged fragmentary plan view of a portion of the boat bottom as illustrated in Fig. 2, showing the action of the offsets on the flow of water contacting the vertical surfaces of the jogs;

Fig. 6 is a bottom view of a boat of the planing type, generally similar to the boat shown in Figs. 1, 2, 3, and 4, but in which the embodiment of the present invention incorporates offsets of a greater lateral dimension than those shown in Fig. 2;

Fig. 7 is a side elevational view of a hydroplane of the step type to which the present invention has been adapted;

Fig. 8 is a bottom view of the boat shown in Fig. 5;

Fig. 9 is an enlarged transverse sectional view of the boat shown in the previous two figures taken on the line 9—9 of Fig. 8;

Fig. 10 is an enlarged transverse sectional view of the boat shown in the previous two figures taken on the line 10—10 of Fig. 8;

Fig. 11 is a partially broken side elevational view of the hull of a flying boat, showing the application of the present invention thereto;

Fig. 12 is a bottom view of the boat hull shown in Fig. 11; and,

Fig. 13 is an outline cross-section of the boat hull shown in Figs. 11 and 12, as on the line 13—13 of Fig. 12.

Ideally, a boat having a bottom consisting of one or more flat or nearly flat planing or lifting surfaces, when propelled at speed on the water, would move over the surface of the water rather than through it. Due, however, to the fact that water is a fluid, that the boat has mass or weight, that surface friction occurs between the wetted surface of the boat and the water, and that therefore there is a tendency to displace water, ideal planing never actually occurs. The proximity to which ideal planing is approached is dependent upon the relationship which exists between the mass of the boat, the speed, and the hydrodynamic reaction characteristics of the planing surfaces of the boat.

It is also true in practically all constructions that an entrance wave is created at the line or point where the entering edge first impinges upon the water. This wave is deflected by the force of forward movement of the boat hull in a gen-

erally outward, upward and rearward direction in relation to the hull. This wave, therefore, comes in continuous contact with the planing surface or surfaces and in conventional constructions remains in continuous contact with the planing surface to the outer edges of same. For purposes of analysis the lift or planing effort created by the entrance wave can be considered as an adjunct to that created by certain of the other hydrodynamic phenomena related to the planing surface or surfaces and the forward movement of the boat. It is my theory that this wave factor is of great importance in the action of planing boat surfaces on and in the water, because the outward, upward and rearward movement of the water contained therein not only produces lift, which is a planing aid, but also because it produces increased wetted area due to its adhesion to the planing surfaces and consequently increased resistance to forward movement.

Among the principal objects of the present invention are the elimination of the greater part of that portion of the wetted area due to adhesion and the consequent abnormal raising of the entrance wave, increase of the effective lifting or planing effort created by the entrance wave, and substantial reduction of that portion of the remaining wetted area not producing an effective planing or lifting effort. In other words, one theory of my invention is to so form the planing surfaces as to utilize whatever hydrodynamic lifting effort is required to maintain the boat at the most efficient point of planing, and no more, and to eliminate as far as possible any contact of the hull with the water not directly utilized for lifting purposes.

Specifically, the manner in which this result is accomplished is to form each major planing or lifting surface of a multiplicity of smaller planing surfaces whose greatest dimensions lie in directions preferably varying from parallel relationship with the keel to complementary diagonal relationship on opposite sides of the boat, each of the latter planing surfaces being vertically displaced from the adjoining ones in an upward direction laterally toward the nearer bilge and the stern, thereby forming a jog between each of the latter planing surfaces. Now in accordance with the present invention, these jogs are not of a continuously unbroken character in extending from the corresponding chine to the stern, keel, step or other surface where they run out and their rearmost end, but instead are modified from such a construction. According to one viewpoint, they may be considered as relatively short jogs arranged in series or in groups, each one of each series or group being parallel to the rest of those in the same series or group and inwardly offset toward the keel from that one thereof immediately forwardly thereof. According to another viewpoint, each jog may be considered as continuous as above described, but successive longitudinal portions of which are offset inwardly from one another in a rearward progression, with a sharp break between adjacent offsets.

The action of such a construction in the water is considerably different from that of constructions heretofore proposed. Upon impinging at the keel or entering edge and being deflected in a relatively outward, upward and rearward direction, the water, due to its own inertia, is freed of contact with the planing surface of the boat at the point where these jogs occur, which greatly reduces the area of wetted surface and therefore

the resistance of the boat to forward movement.

With such constructions at certain speeds and on certain portions of the bottom the deflected water will leave the jog and flow relatively outwardly and rearwardly again coming in contact with the next laterally outward planing surface, this action continuing until the water has passed the rearward or the bilge extremities of the boat, or by its own inertia takes a course not in contiguity with the surface of the boat. Again, with such construction and at certain other speeds and on other portions of the bottom the water may be deflected into contact with the generally vertical surface of a jog and adhere thereto, thus defeating the purpose of such jogs at such area, resulting in undesired wetted areas, increased drag, and consequent reduction in efficiency. The offsets in such jogs provided in accordance with the present invention remedy this defect in that where any water tends to adhere to the vertical surface of any jog, as soon as it reaches the rear end of the corresponding offset, due to its own inertia, its adhesion is broken and it is freed of contact with the vertical surface of the jog.

In the ordinary type of stepped hydroplane construction as conventionally practiced, the forward motion of the boat through the water creates a region of reduced atmospheric pressure back of the step or steps and the stern. This low pressure region, in attempting to relieve itself, draws both air and water into the space behind such step or steps or stern, and tends to draw the surface water up into contact with the bottom of the boat, thereby creating resistance to forward motion to a much greater degree than would occur were this low pressure eliminated. The present invention is of material advantage in this respect as the generally longitudinally extending jogs in combination with the rearward movement of the water and air relative thereto and the provision of the offsets to aid in breaking the tendency of the water to adhere to the boat, all as above explained, induces considerable amounts of air that would ordinarily be forced aside to pass under the boat, thereby relieving to a great extent the region of low pressure that would ordinarily exist back of such step or steps or stern.

Generally speaking, the application of the present invention is best made to those types of boat planing surfaces shown and claimed in United States Patent No. 1,935,622, issued Nov. 21, 1933, to George G. Eddy, and United States Patent No. 2,039,586, issued May 5, 1936, to George G. Eddy and myself. The form shown in the latter of these two patents has been selected herein as the type to which the present invention is shown in the accompanying drawings, but it is to be understood that the application of the present invention is not limited to the specific constructions covered by the above identified patents but is broadly applicable to any construction embodying stepped or jogged surfaces of the general type or effect shown.

Referring now to the drawings and particularly to Figs. 1 to 5, inclusive, it will be noted that there is shown in these figures a boat of the planing or semi-planing type having a single major planing area, the particular type of boat shown being what is known commonly as a monoplane. In the novel construction of this type of boat the bottom portions of the bow sections usually show straight, concave or convex V formations and generally flatten out as they approach the stern section which is usually approximately flat or has a very large included angle. The boat shown in

Figs. 1 to 4, inclusive, is of this general type in that its lower surfaces in the bow sections show a generally deep V conformation and the stern sections are of shallower or more nearly flat shape.

The boat shown includes sides 10, deck 12, stern 14, and bottom indicated generally as at 16. As indicated in Figs. 3 and 4, the boat is preferably provided with a keel 18 or equivalent structure, ribs or frame members 20 and 22 of a suitable nature, and stringers 24 of generally longitudinal disposition. Each side or panel of the bottom 16 on opposite sides of the keel 18 is complementary to the other side, both sides being symmetrically arranged with respect to the keel and to a plane of symmetry passing centrally through the keel. Each half or panel of the bottom 16 on opposite sides of the keel 18 is formed of a plurality of smaller planing surfaces 26, 28, 30, 32 and 34, each of which extends longitudinally to diagonally of the boat and is separated from the next adjacent planing surface or surfaces by a generally vertical jog or jogs 40, the vertical surfaces of which jogs face outwardly and in directions toward the nearer bilge and the stern. The jogs 40 may continue for full or varying depth from the bilge to the stern or keel. They may fade out at their forward ends, at or adjacent the bilges or chines, or may fade out at or adjacent their rear ends, at or adjacent the stern 14 or the keel 18 depending upon which of these they would intersect if carried through or may fade out at both ends, which is the construction shown by way of illustration and preference. It will be appreciated that where they thus fade out the planing surfaces beyond them and which would otherwise be separated by them merge together in smooth relationship.

In accordance with the present invention the jogs 40, or at least most of them, depending upon their lengths and disposition, are not of a continuously unbroken character, but rather each is made up of a plurality of shorter parallel portions each of which is inwardly offset or displaced from that portion immediately forwardly therefrom, toward the keel. On the other hand, each of such short portions may itself be considered as a jog 40, and such portions thus arranged in groups, the portions of each group being parallel in plan, or approximately parallel, with each other, and progressively offset from one another toward the keel in rearward progression. In such case the jog portions 40 of each group are arranged in complementary relation on either side of the plane of symmetry passing centrally through the keel, the jog portions of all groups preferably, but not necessarily in all cases, being arranged at an acute angle with respect to such plane in rearwardly converging relation with respect thereto and preferably with increasing angularity in outward progression from such plane, as shown.

Regardless of how the above is considered, there is a sharp break between each succeeding portion of each jog 40, when considered as first described, or between each pair of adjacent jogs 40 of each group when considered as last described, forming a lateral surface 42, best brought out in Fig. 5. These surfaces 42 are not required to be perpendicular to the lengths of the corresponding jogs 40 or portions thereof, but their outer edges should join or intersect the forward of the corresponding jogs or portions 40 at a sufficient angle to provide the sharp break required to free water, under its own inertia, flowing along the jog 40 or portion thereof imme-

diately forwardly thereof, when the boat is traveling at speed. In the particular form of the surfaces 42 shown by way of illustration, the planes of the surfaces 42 are perpendicular to the planes of the corresponding jogs or portions 40 which they connect, at their outer ends, and are curved into merging relationship with the rearward-most of such corresponding jogs or portions 40 at their inner ends. Each such portion of the jogs 40, or each jog 40 of each said group, depending upon how considered, are preferably, but not necessarily, of the same or approximately the same length or longitudinal dimension.

In the operation of the above described boat, and referring particularly to Fig. 2, let it be assumed that with the boat at speed the water will first impinge upon the boat at a point on the keel such as X. The impingement of the water on the boat will cause what is commonly known as an entrance wave and which entrance wave will be deflected and have a relative flow along a line such as "A" rearwardly, outwardly and upwardly with respect to the bottom of the boat. In conventional constructions, this entrance wave which necessarily spreads as it moves relatively rearwardly, outwardly, and upwardly, will remain in contact with the bottom of the boat for the full distance from the keel to the outer edge of the bilge or chine, even when such edge is well above the normal surface of the water over and through which the boat is moving. The reason for this occurrence in conventional constructions is that the bottom of the boat is a smooth unbroken surface and the adhesion of water to such a surface carries the entrance wave on up the bottom until it is finally freed at the outer edge of the bilge, which bilge, if it be of the hard-chine form as shown, exercises the same functions as the above described jogs but in a minor and much less effective way.

Now in accordance with the present invention when incorporated in a boat of the type shown in Figs. 1 to 5, inclusive, when the boat attains its speed the bow will tend to lift and the boat will tend to have a planing action on the water. Accordingly, due to the fact that the water has an outward, upward and rearward movement relative to the bottom of the boat, there will be a reaction between the bottom of the boat and the water such as is illustrated on the lefthand side of Fig. 3.

Referring now to Fig. 3 it will be noted that due to the outward, upward and rearward motion of the water relative to the bottom of the boat, and particularly when the boat is at speed, the water in passing outwardly, upwardly and rearwardly over the outward edge of the surface 26 will not strike the surface 28 until it reaches a point thereon materially spaced from the jog 40 separating these two surfaces and consequently will leave a portion such as 36 of the area of surface 28 free of contact with the water. The size of the area 36 will depend upon the vertical dimension of the jog 40, the angle which the jog 40 makes with the direction of motion of the water, the relative velocity of the water, the degree of V in the bottom of the boat, and the weight, breadth and speed of the boat.

This entrance wave in having a relative rearward, upward and outward flow with respect to the bottom of the boat will then flow rearwardly, upwardly and outwardly over the surface 28 until it reaches the next outward jog 40 separating the surface 28 from the surface 30 at which point it will break away from the surface 28 and flow directly outwardly and rearwardly without coming

in contact with the surface 30 and consequently will not wet such surface nor burden it with its resistance, assuming that the surface 30 as represented in this section is above the normal surface 5 of the water over and through which the boat is moving. Consequently, in the condition assumed in Fig. 3, the only wetted portion of the bottom of the boat in the section which this figure represents will include only the surface 26 and a part 10 of the surface 28 and the wetted area of the bottom of the boat will, therefore, be materially reduced over the corresponding wetted area of boats having bottoms of conventional construction.

Referring now to Fig. 4, it is assumed that the outer edge of the bilge 32 at which this section is taken is below the normal surface of the water over and through which the boat is moving. Consequently, the water which is moving relatively outwardly, upwardly and rearwardly is in contact with the full width of the surface 26 and with a portion of the width of each of the surfaces 28, 30 and 32, which includes the full breadth of the bottom of the boat at this section. The jogs 40, due to air-water friction and to the relatively rapid lateral movement of water beneath, induce a portion of the air which they are constantly containing into intimate mixture with the boundary layer of water in the form of small bubbles, which action is represented on the lefthand side of Fig. 4.

30 The result of this action is that the boat moves substantially over and through a layer of water containing air in bubble form which offers less resistance to forward motion than water of a normal consistency. It is my theory that this presence of an aerated layer of water for the boat to ride on is one of the reasons why a boat built in accordance with the present invention is capable of attaining a greater speed than when built in accordance with conventional constructions, power and load being equal.

Referring again to Fig. 2, in the after or rearward regions of the planing surfaces where the water, through and over which the boat is moving, has acquired varying degrees of momentum in the direction of the boat's travel, the transverse extent of each area 36 is greatly reduced and in fact at certain speeds and in some portions of the bottom would cease to exist were it not for the lateral surfaces 42 which break adhesion of the 45 water to the vertical surfaces of the jogs 40 and thus effect the induction of additional air from the atmosphere and from the air in water solution and from that in bubble form and finally, therefore, result in the reestablishment and continued 50 establishment of areas 36 over much of the boat's bottom. This is particularly brought out in Fig. 5 wherein the water is shown as flowing in contact with the vertical faces of some of the jogs 40, and being broken from contact with the forward portion of succeeding jog or portion 40 in passing 55 over the intervening surface 42, forming an air space or pocket 36 in the same manner as the air spaces or pockets 36 previously described. Again, since the transverse extent of any area 36 is largely dependent upon the relative velocity of the water coming off of the preceding planing surface at a jog 40, the lateral surfaces 42 contribute an 60 additional measure to the inducement of areas 36 through their continuing induction of air into the jogs 40, with consequent lessened resistance to the relative flow of water under the bottom and the 65 then resultant higher relative velocity of the water coming off of the planing surfaces 26, 28, 30, 32 and 34.

70 With further reference to Fig. 2 and in ad-

ditional discussion of the functioning of the lateral surfaces 42, let it be assumed that with the boat at speed a portion of the water contained in the entrance wave will flow from a point on the keel such as Y following a line such as B rearwardly and outwardly with respect to the bottom of the boat. In the construction as disclosed in United States Patent No. 2,039,586, above referred to, the water will flow for a distance in a manner similar to that from point X 10 in line A as described above. Due, however, to the above described acquisition of a degree of momentum by the water in the rearward part of the boat's bottom, the water flowing as in line B will adhere to the rearward parts of the vertical surfaces of jogs 40, thus destroying the effectiveness of parts of the otherwise unwetted areas 36 and greatly increasing the resistance of the boat to forward motion. The effect would be still greater in the construction shown in the United States Patent No. 1,935,622, above referred to. Due now to the introduction of the offsets 42 in the present invention, the water flowing as in line B will be freed of adhesion to and will lose contact with the vertical surfaces of jogs 40 at each of the offsets with which it comes in contact, as illustrated in Fig. 5, thus forcing, due to the atmospheric head, the added induction of air into the emptied space and the consequent re-establishment of unwetted areas 36, resulting in a materially reduced head resistance of the boat.

Another important result of the above described conjoined actions is the substantial reduction of the depressant or weighing-down effect of the atmospheric head which inevitably attempts to fill the trough to the rear of the entrance wave by pressing or weighing the boat downward where all previously proposed or conventional smooth-skin or non-jogged constructions are employed. It is evident in the present invention that the creation of air channels by the introduction of jogs 40 open to the atmosphere and the maintenance of air passage throughout their lengths by the provision of lateral surfaces 42 allow free atmospheric access to much of the trough rearward of the entrance wave and in so doing relieves the boat of much of the atmospheric head which it would otherwise carry at speed as added weight, thus resulting in a smaller entrance wave and consequent smaller trough and flatter wake, a positive existence of the entrance wave throughout much of the wetted length of the bottom, and a smaller area of wetted surface of the hull, the final net effects being increased dynamic stability and increased speed as compared to craft built in accordance with conventional constructions, static displacement and propulsive power being equal.

An important general result of the construction provided by the present invention, the elimination of the greater part of the burdening effects of water adhesion, makes possible the use of distinctly convex shapes in the bottom portions of the bow and midship sections resulting in easier and drier riding and materially increased speed and seaworthiness over that obtained with boats having bottoms of conventional constructions.

The relation between the depth of the jogs 40 and the width of the corresponding planing surfaces 26, 28, 30 and 32, or the equivalent, as well as the number of such planing surfaces in relation to the width of the boat, may vary con-

siderably in different designs, depending on the bottom loading, speed and other factors of the particular boat to which they are adapted. Likewise, the amount of lateral offset of successive portions of each jog 40, when each jog is considered as extending from a chine or the bilge to the stern or to the keel, or the offset between successive jogs 40 when each is considered as extending only between the surfaces 42 and arranged in groups as previously explained, may vary considerably depending upon the factors above explained, the relative angle between the jogs 40 and the keel, and other factors. For instance, and as illustrated in Fig. 6, the boat bottom there shown is illustrated as provided with a relatively smaller number of relatively wider planing surfaces 26', 28' and 30', corresponding to the surfaces 26, 28 and 30 of the first described construction, said surfaces being separated from one another by the jogs 40', corresponding to the jogs 40 first described. Also in this case, the amount of offset between the successively offset portions of each jog, defined by the laterally extending walls or surfaces 42', corresponding to the surfaces 42 in the first described construction, are of much greater lateral extent than in the first described construction. Such a construction may be found of more advantage in certain types of boats than the relative arrangement of parts shown in Figs. 1 to 5, inclusive.

Referring now to Figs. 5 to 8, inclusive, of the drawings, it will be noted that in these figures a planing type of boat is represented of the stepped type commonly used for high speed type of boats and modifications of which are commonly used as the hull component or components of a flying boat or seaplane. While two or more steps are frequently employed without departing from the general type and form shown, a single-step as represented is sufficient for purposes of description and definition. The boat shown includes sides 50, deck 52, stern 54, and a bottom including two major planing areas, primary and secondary, indicated generally as at 56 and 58, respectively, and separated from each other by a transverse step 60. Each of the major planing areas 56 and 58 closely follows the general construction of the entire bottom 16 of the boat described in connection with Figs. 1 to 5, inclusive. Specifically, the primary planing area 56 is formed of a series of smaller planing surfaces 62, 64, 66, 68, and 70 arranged in complementary relationship on opposite sides of keel 82 and of a plane of symmetry passing centrally through the keel, and extending diagonally and longitudinally of the boat; each of such planing surfaces being separated from the next adjacent planing surface by an upward jog 90, the vertical surfaces of such jogs facing outwardly and in directions toward the nearer bilge and the stern, which jogs are interrupted in their longitudinal continuity at intervals by lateral surfaces 92, corresponding to the surfaces 42 first described, displaced toward the keel in rearward progression.

Similarly, the secondary planing area 58 is formed of a series of smaller planing surfaces 72, 74, 76, 78, and 80 arranged in complementary relationship on opposite sides of the keel 82, and of a plane of symmetry, passing centrally through the keel, and extending diagonally and longitudinally of the boat, each of such planing surfaces being separated from the next adjacent planing surface by an upward jog 90, the vertical surfaces of which jog facing outwardly and in directions

toward the nearer bilge and the stern, which jogs are interrupted in their longitudinal continuity at intervals by lateral surfaces 92 displaced toward the keel in rearward progression.

The bottom of this boat in passing through and over the water effects a reaction as is represented and in the lefthand sides of Figs. 9 and 10, generally similar to that effected by the construction previously described in connection with Figs. 1 to 5, inclusive, in that the water has a relative flow rearwardly and outwardly with respect to the keel, and because of this relative movement it loses contact with the bottom of the boat at each jog 90 and at each lateral surface or notch 92 with which it comes in contact, thus providing and maintaining through the continual induction of air at speed, an area 86 as represented in Figs. 9 and 10, corresponding to the areas 36 of the first described construction, free of contact with the water.

Likewise the conjoined actions of the jogs 90 and the lateral surfaces 92, which act in the same manner as the surfaces 42 of the first described construction, materially reduce the depressant effect of the atmospheric head which is present in great degree in the operation at speed of conventional planing boats of the smooth-skin type.

In this type of boat as previously mentioned the reaction of the boat with the water when at speed tends to create a region of reduced atmospheric pressure immediately to the rear of the transverse step 60 and this reduced pressure in attempting to relieve itself tends to draw the water up into contact with the rearward major planing area 58 at a point much closer to the transverse step 60 than would otherwise be the case, the result of such tendency when unchecked being to increase the water adhesion effect and the wetted area of the boat bottom and correspondingly decrease its speed. When the bottom of the boat is constructed in accordance with the present invention sufficient of the air contained in the jogs 90 is carried rearwardly along the forward major planing area 56 to the region back of the transverse step 60 to largely relieve the low atmospheric pressure at this point, thereby greatly reducing the detrimental effects which would otherwise exist in considerable degree.

The construction described is particularly adaptable for use in connection with flying boats and seaplanes. This is especially true because of the difficulty often encountered in getting such aircraft off of the water in the beginning of a flight. This difficulty arises from the fact that the sum of the weight of the craft and the depressant effect of the atmospheric head taken as weight is often greater than the lifting effort which the wings can exert at the maximum speed of which the craft is capable while in contact with the water. This difficulty is particularly to be noticed in smooth water conditions, where the existence of a chop would otherwise allow some degree of atmospheric access to the wetted portions of the bottom and thus relieve the aircraft of a certain portion of the load imposed by the atmospheric head. In smooth water conditions and in cases where the static displacement of the aircraft is high in relation to the available power it is usually necessary for the craft to motor or taxi back and forth to stir up waves and then take off, if possible, across such chop in order to become airborne. By the application of the present invention to the hulls of flying boats and the like, the atmospheric access provided to the bottom surfaces of the boat, and

the consequently great reduction of the atmospheric head depressant, materially lessens the lifting force required of the wings to break the hull loose from the water. Likewise, the substantial reduction of adhesion of the entrance wave water to the bottom of the hull contributes materially to the reduction of wing loading at take-off speed and, in reducing head resistance as previously described, permits a higher water-borne speed to be reached for take-off. Additionally, and as described previously in connection with other applications of the invention, the great reduction of adhesion of the entrance wave water to the bottom of the seaplane's hull permits the use of a more efficient hull conformation having in itself a further reduced head resistance and consequent higher water-borne speed for take-off, as compared to seaplane hulls of conventional construction. Seaplane and flying boat hulls constructed in accordance with the present invention will ordinarily have no trouble in raising off the water, even with a calm surface, with wing and power loadings, and indeed may substantially increase these wing and power loadings without incurring the smooth water take-off limitations of conventional hulls. Another advantage made possible by the present invention through its reduction of entrance wave adhesion is the use of distinctly convex hull conformations of more than ordinary deadrise in the forward and mid parts of the primary planing surface with a consequent material lessening of impact in landing, or setting the aircraft down, on the water and in taxiing and taking off in a rough sea. This is of importance in all water-landing aircraft of whatever size since the magnitude of this impact largely determines the strength and, therefore, the weight and cost of the hull structure required, and is of particular consequence in the present larger, longer seaplane hulls since severe impact in the bow and forward portions of the hull imposes longitudinal stresses which are costly, in terms of weight of structure, to resist.

The application of the present invention to a flying boat hull is illustrated in Figs. 11, 12 and 13 from which it will be noted that the boat hull which is indicated generally at 100 in fragmentary form is provided with two major planing areas 102 and 104, corresponding generally to the planing areas 56 and 58 of the construction shown in Figs. 7 to 10, inclusive, and separated from one another by a transverse step 106 corresponding to the step 60. The planing surfaces 102 and 104, while generally of the same arrangement as shown in the preceding construction, are different in this respect in that preferably in accordance with conventional practice the planes of the two major planing surfaces 102 and 104 immediately adjacent step 106 are not disposed in parallel or approximately parallel relation, as are the equivalent planing surfaces illustrated in Fig. 7, but are disposed at an angle with respect to each other, the plane of the rear section 104 being upwardly inclined with respect to the plane of the forward section 102 adjacent the step 106, at an angle of approximately 12 degrees. This last feature may not be necessary in all cases but is believed will be of advantage particularly in the larger sizes of flying boat hulls.

Referring particularly to Fig. 12 it will be noted that the forward section 102 is provided with a plurality of planing surfaces 102a, 102b, 102c, 102d, and 102e arranged symmetrically on op-

posite sides of a plane of symmetry including the keel of the hull or its equivalent and the rear section 104 is provided with planing surfaces 104a, 104b, 104c, and 104d similarly arranged with respect to such plane. These various planing surfaces of the sections 102 and 104 are of the same general character as the planing surfaces of the constructions previously described and are separated from one another in the same section by jogs 108 corresponding with the jogs in the previously described constructions, and the jogs 108 are interrupted by the transverse surfaces 110 corresponding to the transverse surfaces 42 and 92 of the previously described constructions. It will be noted that particularly the rear end of the boat hull shown in plan view in Fig. 12 is not of the square character of the straight marine types of constructions shown in the preceding views, but is rounded off, this being in accordance with conventional flying boat hull practice and in order to provide the streamlined effect necessary to lower the drag thereof in moving through the air.

The section shown in Fig. 13 does not illustrate the thickness of the boat bottom or sides but simply the outline thereof, this particularly in view of the fact that in this type of construction the bottom will usually be formed of relatively thin metal suitably formed to shape. Likewise in the section shown in Fig. 13 it will be appreciated that the jogs 108 are not provided with a square inner corner as in the preceding views where wooden planking is shown, the same being shown rounded or radiused in Fig. 13. Where the bottom is formed from metal and where two or more planing surfaces are formed from the same sheet of metal, it will ordinarily facilitate construction to provide such rounded corners as shown. The essential feature is that the lower edges of the jogs 108, and the outer edges of the surfaces 110, or their equivalent, be sharp as these are the edges which control the breaking away of the water from the cooperating planing and jog surfaces, respectively.

In the application of the present invention to flying boat hulls it will be appreciated that as the flying boat picks up speed on the water the bottom loading, or effective weight of the hull on the water, decreases and as the effective weight decreases and the hull rises relatively with respect to the water the area of wetted surface of the bottom of the hull decreases, contrary to the smooth skin conventional constructions, the drag of the hull in the water thus being materially reduced as the speed of the seaplane increases and consequently its effective weight upon the water decreases. This in itself reduces the adhesion between the boat hull and the water to a great extent and, taken in conjunction with the flow of air along the jogs 108 relieving the atmospheric head tending to hold the boat on the water, results in a construction of vastly superior characteristics from a take-off standpoint.

Although I have shown but three specific examples of the present invention in connection with the drawings, it will be apparent that the teachings herein will be sufficient to permit one skilled in the art to adapt the inventive thought to like devices of different types of construction, and, accordingly, it is to be understood that formal changes may be made in the specific embodiments of the invention described without departing from the spirit or substance of the broad invention, the scope of which is commensurate with the appended claims.

What is claimed is:

1. A boat hull of the planing type having substantially the entire bottom surface thereof comprised of a plurality of generally rearwardly extending distinct planing surfaces arranged in complementary relation on opposite sides of the longitudinal plane of symmetry of said hull, each of said planing surfaces being separated from the next adjacent planing surface by a relatively sharp jog facing generally away from said plane, and said jogs comprising portions constituting a fraction of the length thereof offset toward said plane of symmetry from each other in rearward progression.

2. A boat hull of the planing type having substantially the entire bottom surface thereof comprised of a plurality of generally rearwardly extending distinct planing surfaces arranged in complementary relation on opposite sides of the longitudinal plane of symmetry of said hull, each of said planing surfaces being separated from the next adjacent planing surface by a relatively sharp jog facing generally away from said plane, and said jogs comprising portions constituting a fraction of the length thereof offset toward said plane of symmetry from each other in rearward progression, each of said portions terminating at its rearmost end in a relatively sharp edge.

3. A boat hull of the planing type having substantially the entire bottom surface thereof comprised of a plurality of rearwardly extending distinct planing surfaces arranged in complementary relation on opposite sides of the longitudinal plane of symmetry of said hull and in rearwardly converging relationship with respect to said plane, each of said planing surfaces being separated from the next adjacent planing surface by a relatively sharp jog facing generally away from said plane, and said jogs comprising portions constituting a fraction of the length thereof offset toward said plane of symmetry from each other in rearward progression, each of said portions terminating at its rearmost end in a relatively sharp edge.

4. A boat of the planing type having substantially the entire bottom surface thereof comprised of a plurality of diagonally and longitudinally extending distinct planing surfaces arranged in complementary relation on opposite sides of the longitudinal plane of symmetry of said boat, the medial lines of said planing surfaces increasing in angularity with said plane of symmetry successively rearwardly, each of said planing surfaces being separated from the next adjacent planing surface by a relatively sharp outwardly and rearwardly facing jog, and said jogs comprising a plurality of longitudinally distinct portions offset in rearward progression toward said plane of symmetry.

5. A boat hull of the planing type having substantially the entire bottom surface thereof comprised of a plurality of generally rearwardly extending distinct surfaces arranged in complementary relation on opposite sides of the longitudinal plane of symmetry of said hull, each of said planing surfaces being separated from the next adjacent planing surface by a relatively sharp jog facing generally away from said plane, said jogs comprising portions constituting a fraction of the length thereof offset toward said plane of symmetry from each other in rearward progression, and each of said planing surfaces merging at its rearward end into a fair surface common to the rearward ends of the remaining planing surfaces on the corresponding side of said plane of symmetry.

6. A boat hull of the planing type having substantially the entire bottom surface thereof comprised of a plurality of generally rearwardly extending distinct planing surfaces arranged in complementary relation on opposite sides of the longitudinal plane of symmetry of said hull, each of said planing surfaces being separated from the next adjacent planing surface by a relatively sharp jog facing generally away from said plane, said jogs comprising portions constituting a fraction of the length thereof offset toward said plane of symmetry from each other in rearward progression, and each of said jogs tapering in depth from a maximum in its central portions to minimal at its rearward end.

7. A boat hull of the planing type having substantially the entire bottom surface thereof comprised of a plurality of generally rearwardly extending distinct planing surfaces arranged in complementary relation on opposite sides of the longitudinal plane of symmetry of said hull, each of said planing surfaces being separated from the next adjacent planing surface by a relatively sharp jog facing generally away from said plane, said jogs comprising portions constituting a fraction of the length thereof offset toward said plane of symmetry from each other in rearward progression, and each of said jogs tapering in depth from a maximum in its central portion to minimal at its forward end.

8. A boat hull of the planing type having substantially the entire bottom thereof formed of a plurality of longitudinally separate major planing areas separated from each other in rearward

progression by a vertical step, each of said major planing areas comprised of a multiplicity of generally rearwardly extending distinct planing surfaces arranged in complementary relation on opposite sides of the longitudinal plane of symmetry of said boat hull, each of said planing surfaces being separated from the next adjacent planing surface by a relatively sharp jog facing generally away from said plane, and said jogs comprising portions constituting a fraction of the length thereof offset toward said plane of symmetry from each other in rearward progression.

9. A boat hull of the planing type having substantially the entire bottom thereof formed of a plurality of longitudinally separate major planing areas separated from each other in rearward progression by a vertical step, each of said major planing areas being directed upwardly from such step, from which it rearwardly extends, with respect to the general plane of the preceding major planing area in the region of such step, each of said major planing areas comprised of a multiplicity of generally rearwardly extending distinct planing surfaces arranged in complementary relation on opposite sides of the longitudinal plane of symmetry of said boat hull, each of said planing surfaces being separated from the next adjacent planing surface by a relatively sharp jog facing generally away from said plane, and said jogs comprising portions constituting a fraction of the length thereof offset toward said plane of symmetry from each other in rearward progression.

CHARLES DOUGLAS VAN PATTEN.
